UNITED STATES PATENT OFFICE.

ANNIE M. OTT, OF DENVER, COLORADO.

SKIRT-SUPPORTER.

SPECIFICATION forming part of Letters Patent No. 757,672, dated April 19, 1904.

Application filed November 25, 1903. Serial No. 182,695. (No model.)

To all whom it may concern:

Be it known that I, ANNIE M. OTT, a citizen of the United States, residing at Denver, in the county of Denver and State of Colorado, have invented certain new and useful Improvements in Skirt-Supporters, of which the following is a specification.

My invention relates to devices used for supporting-skirts; and my objects are, first, to provide a skirt-supporter which, being simple in construction, may be readily applied and will most effectually prevent the skirt from sagging, while at the same time holding down the shirt-waist; second, to provide a skirt-supporter which, having a plurality of independent points of contact with the skirt, will hold it securely and prevent tearing of the garment; third, to provide a skirt-supporter which will at no time show above the waistband or become unfastened on account of the strain caused by the weight of the skirt. To these ends I make use of the mechanism illustrated in the accompanying drawings, in which—

Figure 1 represents an enlarged perspective view of the device; Fig. 2, an enlarged section taken along the line 22, Fig. 1; Fig. 3, an enlarged perspective view of one of the skirt-engaging members of the device; Fig. 4, an enlarged perspective view of the pin-engaging member; and Fig. 5, a perspective view showing the device attached to a shirtwaist, the skirt being shown as partly fastened.

Similar reference-numerals refer to similar parts throughout the various views.

My device consists of a safety-pin 5, of the usual construction, comprising a pin-arm 5^a, spring-coil 5^c, shank 5^d, and shield or sheath 5^f. Shank 5^d is provided with the skirt-engaging members 6 and 6, located at the outer extremities of said shank, one adjoining spring-coil 5^c, while the other adjoins shield 5^f. They are separated from each other and held in place by the pin-arm-engaging member 7, the aggregated width of the three members being equal to the distance between the spring-coil and the shield 5^f. Members 6 and 6 are plates the upper edge of which has been bent around the shank 5^d, allowing free movement of the plates around the shank, while their opposite or lower extremities have been bent upward and

are provided with a number of points or prongs 6^b. The third or middle member 7 is also a plate, one edge of which is bent around the shank, from which point it tapers toward its free extremity, which is bent upward, forming 55 a hook 7^a, which when the member 7 is moved upward will engage the pin-arm 5^a, as shown in Fig. 1, in which the locked position of plate 7 has been shown in full lines and its unlocked position in broken ones.

Fig. 5 illustrates the mode of applying my device. The safety-pin 5 having been secured to the shirt-waist 10, member 7 is placed in the locking position, its hook engaging the pin-arm. The shirt 12 when placed over the shirt-waist will by its weight cause skirt-band 12^a to engage the upwardly-extending prongs of the members 6, thereby securely attaching the skirt to the waist.

The necessity of the pin-arm-engaging member 7 will be readily understood if it is taken in consideration that the weight of the skirt (which often is considerable) causes a constant downward strain on the shank of the safety-pin. If the member 7 were omitted, 75 this strain while pulling the shank 5^d downward would naturally cause the pin-arm to bend, with the result that it eventually would appear above the waistband of the skirt and if bent still farther would fail to engage the 80 shield, and consequently detach the skirt from the waist.

Another advantage of great importance gained in my device is the fact that I provide two points of contact with the skirt-band a 85 certain distance apart instead of having one plate, as is sometimes used in devices of this kind. My construction allows the skirt-band to conform to the rounding shape of the figure without having to bend or strain the 90 plates, which invariably results in the tearing and eventually loosening of the garment. It furthermore assures a better and more lasting contact of the device with the skirt-band, as the strain caused by the weight of the skirt is 95 distributed to more than one point on the skirt-band.

Although the form of my device as shown in the drawings is preferable, it will be understood that the shape and proportion of the 100

various parts may be changed without departing from the spirit of the invention.

Having thus described my invention, what I claim is--

- 5 1. In a device of the class described, the combination with a safety-pin provided with a plurality of downwardly-extending skirt-engaging members, of a hook, movably secured to the shank of said pin and adapted 10 to engage the middle portion of the pin-arm when the device is in place, substantially as described.
- 15 2. In a device of the class named, the combination with a safety-pin having two pronged hooks depending from its shank, of a third hook hinged to the shank of said pin in between the first-mentioned hooks and adapted to engage the pin-arm, substantially as described.
- 20 3. In a device for supporting skirts, the combination with a safety-pin, comprising a shank and a spring-arm, of three adjacent hooks hinged to the shank of said pin, the

outer ones of said hooks being adapted to engage the skirt while the middle one is adapted 25 to engage the spring-arm of said pin, substantially as described.

4. In a device of the class named, in combination, a safety-pin, two skirt-engaging members consisting of plates, one extremity of 30 which is movably connected with the shank of the pin, while their opposite extremities are provided with upwardly-extending prongs, and a third member located between the two skirt-engaging members, said third member 35 consisting of a plate, one extremity of which is bent around the shank of the pin, while its free extremity is provided with a hook adapted to engage the pin-arm, all substantially as described. 40

In testimony whereof I have affixed my signature in presence of two witnesses.

ANNIE M. OTT.
